DIFFUSER FOR A LIGHTING FIXTURE

Richard W. Carroll, Los Angeles, Calif., assignor to
U.S. Industries, Inc., New York, N.Y.

Filed Sept. 4, 1969, Ser. No. 19,017

Term of patent 14 years

Int. Cl. D26—06

U.S. Cl. D48—16

Fig. 1

Fig. 4

Fig. 2

Fig. 5

Fig. 3

FIG. 1 is a perspective view of a portion of a diffuser for a lighting fixture showing my new design;

FIG. 2 is a top plan view of a portion of a diffuser;

FIG. 3 is a bottom plan view thereof;

FIG. 4 is an end elevation as seen from the right of FIG. 2; and

FIG. 5 is an end elevation as seen from the left of FIG. 2;

The diffuser is understood to have indeterminate length and width.

I claim:

The ornamental design of a diffuser for a lighting fixture, substantially as shown and described.
